UNITED STATES PATENT OFFICE.

ALFRED LUCKIE AND TYLER L. MANGUM, OF BIRMINGHAM, ALABAMA.

DIAL MECHANISM FOR AUTOMATIC TELEPHONES.

Application filed March 28, 1927. Serial No. 179,156.

Our invention relates to dial telephones, and is concerned with the provision of means to protect from defacement dust and wear the dial numerals and symbols or letters 5 over which the movable dial works.

One object is to attach to the movable dial transparent protecting means disposed below the finger holes and if desired to display the digits and signal symbols on the 10 under side of the protecting means when same will be free from defacement or dust and such numerals or symbols can be applied with luminous paint to increase their visibility through their transparent carrier. 15 A further object is to provide telescoping protecting disks which will effectively exclude dust and dirt from the number dial without interfering with the freedom of manipulation for the movable dial. 20 A further object is to provide the circular casing in which the fixed dial has heretofore been mounted with an upstanding annular flange adapted to telescope into a flange depending from the movable dial, the flanges 25 permitting the interposition under the openings in the movable dial of a transparent annulus adapted to prevent access of dust through the top openings to the dial numbers or marks. 30 A further object is to form the protecting annulus with depressions or pockets arranged to correspond with the finger holes in the movable dials, the annulus being adapted to be mounted in a novel and effective 35 way in the flange of the movable dial so as to give a practically dust proof closure.

A further object is to provide the depressions in the transparent annulus so that they 40 deepen in the direction of manipulation of the dial, thereby to present a more abruptly inclined wall on that side of the depression and thus facilitate the manipulation of the movable dial by pencils or the like and to increase the grip when operated by the 45 finger.

Our invention further comprises the novel details of construction and arrangements of parts, which, in their preferred embodiments only, are illustrated in the accompanying 50 drawings which form a part of this specification, and in which:

Fig. 1 is a side elevation of a dial telephone base equipped with our invention, with the dial mechanism partly broken 55 away.

Fig. 2 is a plan view of the movable dial.

Fig. 3 is a plan view of the transparent annulus showing the dial digits on its under face.

Fig. 4 is a plan view of the base carrying the standard fixed number dial. 60

Fig. 5 is a cross-section taken on the line V—V of Fig. 2.

Fig. 6 is a detail cross-section taken on the line VI—VI of Fig. 3. 65

Similar reference numerals refer to similar parts throughout the drawings.

In the embodiment of our invention illustrated, we show in part a conventional telephone instrument having mounted on its 70 base 7 a fixed cup-like housing 8, which in our present construction will be provided with an extension flange 9 rising almost to the level of the annular central support (not shown), which projects through the bottom 75 opening 10 in the casing upon the top of which the telephone number plate 11 is usually mounted. A fixed dial 12, annular in shape, is mounted in the housing and upon this dial are usually displayed successively 80 the nine digits and a cipher and also such letter or call symbols as may be desired. Rotatably mounted above the dial 12 is a movable dial 13 having openings 14 therein above the several digits and symbols on the 85 fixed dial 12. This dial 13 corresponds to the present standard dial except that it is formed with a marginal depending annular flange 15 which telescopes over the flange 9 on the housing. The telescoping flanges 90 have sufficient clearance to avoid frictional contact which might slow up the travel of the movable dial.

On the inner surface of the flange 15 we provide preferably a very slight annular 95 shoulder 16 with a very slight taper downwardly and which terminates above in an annular seat 17 in the inner face of the dial flange 15 adapted to snugly receive a transparent annulus 17 which is adapted to be 100 snapped into position by being pressed upwardly over this taper shoulder. In the groove we provide at least one lock lug 18 which is adapted to be received in a notch 19 in the periphery of the transparent annulus, thereby holding it in the groove 105 against rotation. This annulus can be so mounted in the groove that it will be pressed snugly against the underface of the movable dial and provide a practically dust- 110 proof closure for the finger holes therein. The annulus is formed with depressions 20

adapted to register with each of the movable dial holes 14, these depressions being deepened towards the right to afford a better purchase for a pencil or the like instrument 5 in operating the dial and also to increase the finger grip. The depressions however should not be deep enough to make it difficult to keep them clean.

We have described the annulus as of flexible transparent material, but our invention 10 contemplates that the annulus may be of any transparent material and that it may be mounted in any manner that will afford substantially dust-proof protection under 15 the openings in the top of the movable dial. Our invention contemplates that the transparent annulus attached to the underside of the movable dial may, if desired, be connected thereto with a suitable adhesive to 20 more effectively seal the joints, and that the numerals and symbols displayed on the lower dial may be displayed by luminous 25 paint as at 21 on the underside of the transparent annulus, i. e., on the underside of the 30 depressions 20 therein. The telescoping members when associated with the numeral-bearing annulus will protect such numerals from dust and dirt and from defacement and, due to the fact that the movable dial is 35 stopped in its forward movement by the stop arm 22 and returns automatically to its starting position, this dial can be manipulated either by a movement thereof relative to the fixed dial numerals or by a movement 40 thereof with reference to the dial figures carried by the transparent annulus on the movable dial. The figures are below the transparent annulus in both forms of 45 our invention and they will be protected from defacement thereby. Our invention 50 when assembled will effectively protect the dial digits and symbols without interfering at all with the manipulation of the movable dial to signal.

Though we have described with great particularity the details of the embodiment of the invention herein shown, it is not to be construed that we are limited thereto, as changes in arrangement and substitution of 55 equivalents may be made by those skilled in the art without departing from the invention as defined in the appended claims.

Having thus described our invention, what we claim as new and desire to secure 55 by Letters Patent, is:

1. In a telephone dial mechanism, a rotat-

able dial plate carrying a series of finger holes closed below by a transparent element rotatable with the dial plate, a series of signal indicia visible through said holes, and 60 stop means to limit rotation of the dial in signalling.

2. A telephone dial mechanism according to claim 1, in which the signal indicia are applied to the underface of the transparent 65 element.

3. A telephone dial mechanism according to claim 1, in which the transparent element provides a socket co-extensive with its respective dial hole and having greater 70 depth in the direction of the dial's forward operating movements.

4. A telephone dial mechanism according to claim 1, in which the transparent element is in the form of an annulus having 75 marginal sockets formed therein to register with the holes in the movable dial.

5. In a telephone dial mechanism, a cup-like receptacle, a rotatable dial having a marginal flange telescoping about said receptacle, a stop for the dial carried by said receptacle, there being finger holes in said dial, a transparent cover mounted inside the dial to close said holes against access of dust to said receptacle, and signal indicia disposed to be visible through said transparent cover and in position to be projected by said cover and telescoping walls from dust and defacement.

6. A telephone dial mechanism according to claim 5, in which a fixed dial is mounted 90 in said receptacle and displays said signal indicia.

7. In a telephone dial mechanism, a rotatable dial having finger holes and a marginal downturned flange, and a transparent annulus engaged in said flange and provided with depressions registering with said holes in the dial.

8. In a telephone dial mechanism, a rotatable dial having finger holes and a marginal downturned flange, a transparent annulus engaged in said flange and provided with depressions registering with said holes in the dial, and interlocking elements on the dial and annulus to hold the latter against 100 relative movement on the dial.

In testimony whereof we affix our signatures.

ALFRED LUCKIE.
TYLER L. MANGUM.
